UNITED STATES PATENT OFFICE.

FRANK KUHN AND JAY A. HAND, OF DETROIT, MICHIGAN, ASSIGNORS TO AMERICAN ELECTRICAL HEATER COMPANY, OF DETROIT, MICHIGAN, A CORPORATION OF MICHIGAN.

DESIGN FOR A STOVE.

53,416.

Specification for Design.

Patented June 10, 1919.

Application filed February 21, 1918. Serial No. 218,583. Term of patent 14 years.

To all whom it may concern:

Be it known that we, FRANK KUHN and JAY A. HAND, both citizens of the United States of America, and both residing at Detroit, in the county of Wayne and State of Michigan, have invented a certain new, original, and ornamental Design for Stoves, of which the following is a specification, reference being had therein to the accom-

panying drawings, forming part thereof, in which the figure represents a perspective view.

We claim:

The ornamental design for a stove, substantially as shown.

FRANK KUHN.
JAY A. HAND.
